UNITED STATES PATENT OFFICE.

ROBERT H. MEHL AND ROBERT KNOTT, OF BROOKLYN, NEW YORK.

CANDLESTICK.

SPECIFICATION forming part of Letters Patent No. 380,506, dated April 3, 1888.

Application filed June 7, 1887. Serial No. 240,523. (No model.)

To all whom it may concern:

Be it known that we, ROBERT H. MEHL and ROBERT KNOTT, both of Brooklyn, in the county of Kings and State of New York, have invented 5 a new and Improved Candlestick, of which the following is a full, clear, and exact description.

Our invention relates to a pendent candlestick designed more particularly for lighting and ornamenting Christmas-trees, &c.; and the 10 invention consists of a candlestick constructed and combined as hereinafter described and claimed.

Reference is to be had to the accompanying drawing, forming a part of this specification, 15 in which the figure is a perspective view of our new and improved ornamental candlestick.

A represents a standard of wire, bent at the lower end to form the arm B, on which is placed the plate C, which has secured to its center a 20 socket or the fingers *aa*, for holding the candle D. In line with the candle D is secured to the standard A the reflector E, and above the reflector the standard A is bent to form the loop or hook F, for attaching the candlestick 25 to the limb of a tree or other support. From

the loop F the standard is extended upward and bent at *b*, and again at *c*, to form the upwardly-projecting extension *d*. Upon this is placed the wind-wheel G, which is held in the upward current of air from the candle and 30 caused to constantly revolve, thus giving the candlestick a very striking and handsome appearance.

Having thus fully described our invention, we claim as new and desire to secure by Letters 35 Patent—

In a candlestick, the wire A, bent at its lower end to form the supporting-arm B, and bent near its upper end to form the loop F, and also bent above said loop, as at *b* *c*, to form the 40 extension *d*, in combination with the reflector E, secured to said wire below the loop, and the pin-wheel G, pivoted upon the extension *d*, substantially as described.

ROBERT H. MEHL.
ROBERT KNOTT.
